UNITED STATES PATENT OFFICE.

JOHN D. LADD, OF NEW YORK, N. Y., ASSIGNOR TO THE NEW YORK
OTTOMAN AND HASSOCK COMPANY, OF SAME PLACE.

DESIGN FOR AN OTTOMAN.

Specification forming part of Design No. 6,457, dated February 15, 1873.

To all whom it may concern:

Be it known that I, JOHN D. LADD, of the city, county, and State of New York, have invented a Design for an Ottoman, of which the following is a specification:

The nature of my design is fully represented in the accompanying photographic illustration, to which reference is made.

My design consists of the general form and configuration given to an ottoman, shown in the illustration, the frame of the ottoman consisting of six sides, the same being beveled inward toward the center from both the seat and the base, as shown, each side being also beveled inward longitudinally, so that they all match into and conform to the configuration

of the base and seat, which are made in the shape of a star, as shown in the illustration. The ottoman is covered with a suitable fabric of any desired pattern, but preferably with carpet, and given a tasteful and ornamental finish at the base and around the edge of the seat, and at the star-points of the seat, as shown in the illustration.

What I claim, and desire to secure by Letters Patent, is—

The design of an ottoman, as shown.
JOHN D. LADD.
